UNITED STATES PATENT OFFICE.

DUSTIN F. MELLÉN, OF NEW YORK, N. Y.

IMPROVED DEVICE FOR GRIPING SCREW-BLANKS.

Specification forming part of Letters Patent No. 58,446, dated October 2, 1866.

To all whom it may concern:

Be it known that I, D. F. MELLÉN, of the city, county, and State of New York, have invented certain new and useful Improvements in Screw Machinery, consisting of a spindle to be used in threading-machines, shaving-machines, or other places where said spindle is applicable; and I do hereby declare and ascertain my said invention, referring to the accompanying drawings, in which—

Figure 1 is a longitudinal section through the spindle. Fig. 2 is a portion of the front end of the spindle complete. Fig. 3 is an outline of the spindle with the rings, &c., removed. Fig. 4 is a section at x x of Fig. 1. Fig. 5 is a section at y y of Fig. 1. Fig. 6 is a section at z z , Fig. 2.

My improved spindle is intended to seize and hold the blanks for metal screws and other like articles, and revolve them against the cutting-tools in the several processes of manufacture, where it is applicable.

The construction is as follows: I form my spindle in two parts, divided on one side of the plane of the axis, the division-line being indicated by the number 1. It extends back as far as 2 (see Fig. 3,) which shows the exterior outline of the spindle with the rings and other outside parts removed. This spindle is made hollow, as clearly indicated at 3, Fig. 1. In the front end of the recess a pair of forceps, 4, are placed, the jaws of which extend to the front end of the spindle. These jaws are formed to grasp the article to be held by them, as indicated by the dotted lines, showing the outline of the head of a screw-blank. The fulcrum or pivot of these forceps 4 is at 5, and the shanks run back some distance, as shown in the drawing, Fig. 1, within the recess, in which also there is a spring, 6, that bears on the shanks of the forceps on each side, to hold the jaws open. Just behind the forceps 4 is placed another pair, 7. The jaws of these are between the shanks of the others, as seen in Fig. 1, and bear against them, which action closes the jaws of forceps 4. The fulcrum of forceps 7 is at 8, and is adjustable in a manner hereinafter described. The shanks of these forceps project back and bend outward, so as to extend beyond the outer surface of the spindle, through which there is an opening

for the purpose. By bearing these projecting shanks inward, it will be seen their jaws open against the shanks of forceps 4 and close their jaws upon the article inserted between them. As this has to be done while the spindle is in rapid revolution, a peculiar apparatus to effect this will be hereinafter described.

The two halves of the spindle are connected by two screws. The front screw 5 serves to pivot forceps 4. The screw 9 simply connects the other end. The parts are firmly bound together, first, by a nose-piece or ring, 10, screwed onto the front end of the spindle and beveled off to the proper shape. Directly behind this ring 10, I put on a hardened steel ring, 11, which is formed thicker at the center than at the edges, so as to have two conical surfaces. This forms the front bearing of the spindle and revolves in double boxes 12, so made as to be set up as the parts wear, to insure accuracy in running the spindle. This device is seen in Fig. 1, and is important.

A ring, 13, is put onto the spindle over the point where the fulcrum 8 of the forceps 7 is. This fulcrum is made to project through oblong holes in the spindle, (seen by dotted lines in Fig. 2,) and is firmly secured by screws to said ring. On each side of the ring 13 are nuts screwed onto the spindle, by which the ring can be moved either way, and firmly set so as to adjust the fulcrum 8 of the forceps 7, as required, to regulate the gripe of the forceps 4 in using different sized wire, and to compensate for wear.

The pulley for driving the spindle may be placed just behind this ring 13, and near the rear bearing of the spindle may be placed gear-wheels 14 17, to gear with other parts of the machinery. The rear bearing is at 15, and consists of a hardened ring embracing the spindle and running in a box, 16, so made as to be tightened as the parts wear, but straight and cylindrical on the wearing-surface, so as to allow end play for expansion, &c. The only other part essential to the working of the spindle is the apparatus that opens and closes the forceps 4, by acting on the projecting shanks of forceps 7. It consists of a ring, 18, on the outside of which are two trunnions or lugs, by means of which said ring can be made to slide sidewise by any of the ordinary shift

movements on the spindle. This ring does not revolve with the spindle; consequently, when it comes in contact with the shanks of the forceps 7, over which it slides to depress them while they are in rapid revolution, the parts would soon wear so as to be inoperative. To obviate this I form a recess within the ring, on its inner face, and insert therein a hardened steel ring, 19, which alone comes in contact with the shanks of the forceps, and as this ring is loose and free to revolve in the outer one, as soon as it binds upon the forceps it takes their motion, and produces no wear except simply slipping on and off between those parts, and it will be noticed that, however much it becomes loose in the outer ring, its action on the forceps is not affected. When this ring 19 is slipped onto the shanks of forceps 7 the jaws of forceps 4 are closed thereby, and when it is slipped off they are opened by springs b.

Having thus fully described my improvements in spindles of screw and other like machinery, what I claim as new, and for which I desire to secure Letters Patent, is—

1. A hollow spindle, in which forceps or some other analogous device is placed, made in two parts by a longitudinal division, substantially as and for the purposes set forth.

2. The adjustable fulcrum 8, for the adjustment of the forceps, regulated by the screw-nuts around the spindle, by which it is shifted and held, substantially as and for the purposes set forth.

3. Inserting folding springs 6 within the spindle, to open the jaws of the forceps, constructed, arranged, and combined with the forceps and spindle, as and for the purposes set forth, it being understood that I do not claim springs *per se*, to open the jaws of the forceps, they having before been essayed, but in a different way and of different construction.

4. The hardened steel bearings 11, combined with the spindle and box 12, substantially as herein specified.

5. The hardened bearing and box 15 and 16, in connection with a forward bearing that will not allow end chase, constructed and arranged substantially as and for the purposes specified.

6. The sliding ring 18, and hardened ring 19, for closing the forceps, substantially as herein set forth.

DUSTIN F. MELLEN.
